UNITED STATES PATENT OFFICE.

JOSEPH SAMUEL BEEMAN, OF LONDON, ENGLAND.

CIGARETTE-MOUTHPIECE-APPLYING MACHINE.

SPECIFICATION forming part of Letters Patent No. 662,389, dated November 27, 1900.

Application filed February 19, 1900. Serial No. 5,788. (No model.)

To all whom it may concern:

Be it known that I, JOSEPH SAMUEL BEEMAN, a subject of the Queen of England, residing at 182 Earl's Court road, London, England, have invented certain new and useful Improvements in or Relating to Cigarette-Mouthpiece-Applying Machines, of which the following is a specification.

This invention relates to improvements in cigarette-mouthpiece-applying machines, and has particular reference to machines in which a strip of cork, paper, tobacco-leaf, or like material coated with an adhesive is applied as a "tip" to the end of the cigarette.

A machine according to this invention comprises the following chief elements: a holder for the cigarette, a "retainer" to which a strip is caused to temporarily adhere, means for supplying an adhesive or moistening agent to the retainer, means for presenting a strip to and contacting it with the retainer, and a lifting device which disengages the strip or a portion thereof from the retainer and brings its under surface into contact with the cigarette to which it is to be applied. Preferably means are also provided to bring the strip after it has been presented to the retainer into more intimate contact therewith, and a tapping and smoothing device is employed to insure the proper application of the strip to the cigarette end after it has been brought thereto through the action of the lifting device.

In order to secure the uniform tipping of the cigarettes, which vary somewhat in length, the mechanism which feeds them to the holder is conveniently arranged to protrude each cigarette too far through the holder, and a movable stop is then brought into action, which partially returns the cigarette, so that the protruded portion is of a definite length.

In the accompanying drawings, which illustrate one construction of machine according to this invention, Figure 1 is a longitudinal vertical section on the line 11 of Fig. 2. Fig. 2 is an end elevation, looking in the direction of the arrow in Fig. 1, partly in section and with portions removed for the sake of clearness. Fig. 3 is a cross-section on the line 33 of Fig. 1. Fig. 4 is a plan showing a portion of the operating mechanism, and Figs. 5, 6,

and 7 are perspective views illustrating portions of the machine.

Like letters indicate like parts throughout the drawings.

55

A is a base-plate upon which the stationary portions of the machine are rigidly mounted. Standards A¹ and A², attached to the base-plate, carry in bearings a shaft B, from which the various mechanisms are driven. The shaft B may be rotated by power supplied to a pulley B' or manually by means of a crank-handle B², keyed to the end of the shaft. The pulley B' is arranged so that it may be engaged or disengaged with the shaft by 65 means of a clutch. A handle for throwing the pulley B' into or out of gear is shown at B³. The shaft B carries cams B⁴, B⁵, B⁶, B⁷, B⁸, and B⁹, which are hereinafter more fully described. Standards A³ and A⁴, attached to 70 the base-plate A, support a chamber or hopper C, into which the cigarettes are placed. A portion C' of the bottom of the chamber C is hinged, as at C², and is provided with a projection C³, carrying a friction-roller C⁴. This 75 friction-roller C⁴ works in conjunction with the cam B⁵, and thus the hinged portion C' is oscillated and forms an agitator for preventing bridging or jamming of the cigarettes in the chamber C. The cigarettes pass from the 80 chamber C through a conduit C⁶ to a trough C⁷. In line with the trough C⁷ and supported in bearings in a bracket A⁵, attached to the standard A³, is a holder D, provided internally with a light spring D', which slightly grips 85 the cigarette. The holder D carries a pinion D², which engages with the teeth upon a portion of the circumference of a disk D³, carried upon the shaft B. The number of teeth upon the circumference of the disk D³ and the 90 diameter of the pinion D² are such that the holder D makes about five complete revolutions during one rotation of the shaft B. The holder is of course stationary during the time that the plain portion of the circumference 95 of the disk D³ is adjacent to the pinion D². A spring D⁴, Fig. 5, presses upon the holder D and acts as a brake to prevent undue rotation. In Fig. 5 the front wall of the chamber C is removed.

100

The cigarettes S, Fig. 5, are caused to pass from the trough C⁷ into the holder D by the

action of a plunger E, which is attached to a slide E', moving upon a guide E'', carried between the standard A⁴ and another standard A⁵. One end of a lever E³ engages loosely with the upper portion of the slide E', the other end of this lever being pivoted at the top of a standard A⁶. A forked arm E⁴, controlled by a spring E⁵, is carried by the standard A⁶ and is rigidly attached to the arm. 10 This forked arm E⁴ engages with a pin E⁶ upon an arm E⁷, pivoted to a standard A⁷ and carrying a friction-roller E⁸. This friction-roller E⁸ works in conjunction with the cam B⁴, and when the shaft B rotates the action 15 of the cam B⁴ upon the friction-roller E⁸ causes the arm E⁷ to turn, and thus through the pins E⁶ and forked arm E⁴ makes the lever E³ turn against the action of the spring E⁵. The plunger E therefore moves forward and 20 pushes a cigarette from the trough C⁷ into the holder D, ejecting the cigarette previously in the holder. The return of the plunger E is brought about by the action of the spring E⁵ when the position of the cam B⁴ admits of 25 such movement. The forward motion of the plunger E is such that the cigarette is caused to protrude too far through the holder D.

F is a rigid frame supported upon standards A⁸ and A⁹, attached to the base-plate A. Pivotedally mounted, as at F', upon the frame F is a lever F², the lower end of which carries a stop F³. The other end of this lever carries an adjusting-screw F⁴, which works in conjunction with one end of a bell-crank lever F⁵, pivotally mounted on the frame F, as at F', the other end of which carries a friction-roller F⁶, which works in conjunction with the cam B⁶. The adjusting-screw F⁴ is kept 35 in contact with the upper end of the bell-crank lever F⁵ through the action of a spring F⁸, and this spring thus tends to keep the stop-lever F² in the position shown in Fig. 1. The function of this stop-lever is to partially return the protruded end of the cigarette into the holder, so that a definite length shall remain protruded for treatment. The forward motion of the stop-lever F² is limited by the stop F³ coming into contact with another portion of the machine, hereinafter mentioned. 40

G is a retainer for strips which are to be applied as tips to the cigarettes. It comprises four segmental portions G', having gaps between them. Each of the portions G' is cut away, as at G², leaving two projections G³, 45 whose surfaces are part of the circumference of the retainer G. Each segmental portion G' is provided with a pin G⁴, which assists, as hereinafter described, to keep the strip in place upon the retainer. Upon the back of the retainer are formed four flat surfaces G⁵, which are arranged in the form of a square with the corners cut off, and at the back of this again are four projections G⁶, which act as teeth and work in conjunction with a pawl G⁷, pivoted to the frame F and controlled by a spring G⁸. The retainer G is pivoted, as 50 by a screw G⁹, to a frame G¹⁰, which can re-

ciprocate on guides G¹¹, carried between the standards A⁸ A⁹ and A⁸ A¹⁰, respectively. The reciprocation of the frame G¹⁰ is brought about 70 by the action of the cam B⁷, which acts upon a friction-roller G¹², carried by a lever G¹³, which is pivotally mounted upon a standard A¹¹, Fig. 3. As a portion of the cam B⁷ is circular, the reciprocation of the frame G¹⁰ is intermittent. The lower end of the lever G¹³ is slotted, as at G¹⁴, and a pin G¹⁵ works in this slot, said pin being rigidly connected to the sliding frame G¹⁰. A bar G¹⁶ extends across the machine and is rigidly fixed to the upper 75 portions of the standards A⁸ and A⁹. The lower edge of the bar G¹⁶ though not in actual contact with the flats G⁵ upon the retainer G serves to keep the upper of such flats approximately horizontal during the reciprocation of 80 the retainer. A portion of the bar is cut away, as at G²¹, to allow for the rotation of the retainer when at that spot. Upon the bar G¹⁶ is pivoted, as at G¹⁷, a lever G¹⁸, the other end of which is controlled by a spring G¹⁹, mounted upon the bar G¹⁶, Fig. 3. The downward motion of the spring-controlled pawl G⁷ is limited by a pin G²⁰, which comes into contact with the bar G¹⁶. The under side of the pivoted lever G¹⁸ is approximately flat and 85 acts upon the flats G⁵ at the back of the retainer G, thus serving to keep the retainer in a definite position. When during its reciprocation the retainer is brought into contact with the pivoted pawl G⁷, the nose of that 90 pawl engages with one of the inclined surfaces or teeth G⁶ upon the retainer, and the latter is consequently partly rotated, the spring-controlled lever G¹⁸ being forced up and then coming down upon the succeeding 95 flat G⁵ and securing the retainer in its new position.

H is a flexible band, preferably of tape or similar material, carried upon a bracket H', attached to a frame H², which is rigidly secured to the base-plate A. The lower end of the band H is secured to a block H³, which is mounted upon a spring H⁴, attached to the bracket H'. This arrangement tends to keep the band normally straight, but at the same 100 time allows it to assume a curved shape when required. The band H is supported about midway of its length by a bridge-piece H⁵. Beneath the band H is a stationary receptacle H⁶ for holding an adhesive, and a brush H⁷, carried by an arm H⁸, attached to a sliding piece H⁹, which moves on guides H¹⁰ in the frame H², travels over the band H and keeps it supplied with adhesive from the receptacle H⁶. The sliding piece H⁹ is provided with a 105 pin H¹¹, which engages with a slot H¹² in a lever H¹³, mounted upon the standard A¹⁰ and controlled by a spring H¹⁴. This pivoted lever H¹³ carries a pin H¹⁵, which comes into contact with a portion of a lever H¹⁶, pivoted to 110 the standard A⁸, as at H¹⁷. A friction-roller H¹⁸ is carried upon the lever H¹⁶ and engages with the cam B⁸. During a portion of the operation the friction-roller H¹⁸ is engaged be-

tween a portion of the surface of the cam B^8 and the adjacent portion of another cam B^9 , which is, like the cam B^8 , carried upon one side of the disk D^3 .

5 The mechanism for presenting the strips to the retainer and contacting them therewith comprises a container J , the upper portion of which is furnished with a hinged door J' , Fig. 5. The top of the container J is in the form of two plates J^2 , having a gap J^3 between them. Attached to the bottom of the container J is a pin J^4 , Figs. 1 and 2, one end of which is operated upon by a pivoted lever J^5 , while the other is attached through a spring J^6 , Fig. 1, to a support A^{12} on the base-plate A . The container J is furnished with lugs j , which engage with guides j' , carried on the support A^{12} . The pivoted lever J^5 carries a pin J^7 and is weighted, as at J^8 . The Y -shaped end of a vertical rod J^9 engages with the pin J^7 , the other end of the rod J^9 being pivotally suspended from the lever H^{16} . Within the container J is a relieving-piston, hereinafter described as a frame J^{10} , which is furnished at its lower end with a pin J^{11} and is caused to rise within the container J when the pivoted lever J^5 comes into contact with that pin. Free to slide within the frame J^{10} is an inner plunger J^{12} , which carries a rack J^{13} , which extends through a slot J^{14} in the back of the container J , Fig. 1. Pivoted to the top of the inner plunger J^{12} is an arm J^{15} , one end of which passes through the slot J^{14} and is furnished with a small pin J^{16} , which travels in a slot J^{17} , formed in an extension of the back wall of the container J . A pawl J^{18} , Fig. 1, provided with a handle J^{19} , is pivoted, as at J^{20} , to the lower portion of the container J and is controlled by a spring J^{21} , so that normally it engages with the teeth of the rack J^{13} upon the inner plunger J^{12} . The downward travel of the frame J^{10} is limited by the position of the inner plunger J^{12} , for, as shown in Fig. 1, the frame J^{10} falls until it touches the pivoted arm J^{15} . The amount of inclination of this arm J^{15} depends upon the position of the inner plunger J^{12} relatively to the container J , the arm J^{15} being forced by the slot J^{17} to assume a more vertical position when the plunger J^{12} is near the top of the container. By depressing the handle J^{19} the pawl J^{18} is disengaged from the rack J^{13} , and the plunger J^{12} then falls, providing, of course, that the pivoted lever J^5 is not at the moment exerting an upward pressure upon the frame J^{10} . Strips K are placed in a pile within the container J , the top and bottom ends of the pile being between the under surfaces of the plates J^2 and the top surface of the frame J^{10} , respectively. The number of strips K placed in the container is never so great that there is no play for the lever J^5 between the pins J^4 and J^{11} . Once in every revolution of the shaft B the cams B^8 and B^9 , acting upon the friction-roller H^{18} , causes the lever H^{16} to rise, carrying with it the suspended rod J^9 . This allows one end of the lever J^5 to rise un-

der the action of the weight J^8 , and the container J , acting under the influence of the spring J^6 , at once follows the motion of the end of the lever J^5 and rises until stopped by the upper surface of the top lugs j coming into contact with the top of the support A^{12} . In this position, which is illustrated in Fig. 5, two of the projections G^3 of the retainer G extend downward, so that their lower surfaces approximately coincide with the under surfaces of the plates J^2 . As the end of the lever J^5 rises it comes into contact with the pin J^{11} at the bottom of the frame J^{10} . Consequently that frame rises, carrying with it the pile of strips K , which is compressed, through the action of the weighted lever J^5 , between the frame J^{10} and the plates J^2 . The downwardly-extending projections G^3 have been, as will be hereinafter explained, supplied with adhesive, and consequently the top strip adheres to them when it is raised into contact with them by the frame J^{10} . Continued rotation of the shaft B causes the downward motion of the suspended rod J^9 . Consequently the end of the lever J^5 is depressed against the action of the weight J^8 , and the frame J^{10} falls as far as the position of the inner plunger J^{12} will allow it to do so, thus relieving the upward pressure upon the top strip. The pile of strips follows the frame J^{10} downward, leaving the top strip attached by the adhesive to the retainer G . As the pile of strips K diminishes, owing to successive top strips being removed, the upward motion of the frame J^{10} causes the inner plunger J^{12} to advance upward tooth by tooth of the rack J^{13} . This advance increases the inclination of the arm J^{15} , and consequently the stroke of the frame J^{10} is gradually shortened as the pile of strips K diminishes. This adjustment is found to be useful as tending to compensate for the "spring" which a pile of strips—say of cork—necessarily possesses.

In order that the strips may take a uniform position relatively to the end of the cigarette, a light spring J^{22} , Fig. 1, is provided, which tends to press them to the back of the container J . Two small screws J^{23} , having pointed ends, are provided at the top of the container, their function being to separate the strips if by chance more than one adheres to the retainer.

Pivoted to a lug G^{22} , which forms an extension of the reciprocating frame G^{10} , is a lever L , carrying rigidly attached to it an arm L' , the end of which is shaped, as at L^2 , Fig. 5, so that it can pass through the space between two adjacent segmental portions G' of the retainer G . A finger L^3 , projecting from the portion L^2 , is arranged to move through the space between the projecting portions G^3 of the retainer. The lever L , the arm L' , and their appurtenances constitute a lifting device which lifts a portion of the strip from the retainer and brings its under surface into contact with the cigarette. The lever L is provided with an extension L^4 , having a rounded

nose L⁵, which serves a purpose hereinafter mentioned. A projection L⁶, Fig. 2, is provided upon the back of the lever L. Adjustably secured to a plate M, fixed to the bar G¹⁶, 5 is a plate M', to which is pivoted a pawl M², controlled by a spring M³, which is fixed upon the back of the plate and operates upon a pin attached to the pawl and passing through a slot in the plate. The lever L is controlled 10 by a spring L⁷, which tends to keep it down—that is, so that its lower edge is in contact with a friction-roller L⁸, carried on a bracket L⁹, attached to the bar G¹⁶. When the frame G¹⁰ is reciprocated, the lever L moves with it 15 and the projection L⁶ passes under the spring-controlled pawl M², which rises against its spring to allow it to pass; but when the lever L, carried by the frame G¹⁰, returns the projection rides up the inclined plane formed by 20 the top surface of the pawl M², and the lifting device is consequently raised.

Pivoted to the frame F, as at N', is a lever N, carrying at one end a plate N² and counterbalanced at the other end by an adjustable weight N³. Upon the top of the lever N is an arm N⁴, which when the lever is raised comes under the influence of a spring N⁵, attached to the frame F. This spring N⁵ only operates upon the lever for the first portion of its 25 downward stroke, for a stop N⁶ upon the frame F intercepts the spring before the lever N has reached its lowest position. The function of the lever N is to act as an intermittent tapping and smoothing device to insure the 30 proper application of the strip after it has been brought into contact with the end of the cigarette under treatment. The plate N² is the part which actually comes into contact with the strip, and as it is sometimes desirable that this plate should be heated in order 35 to quickly dry the adhesive upon the strip an extension N⁷ is provided in metallic connection with the plate N², and this extension N⁷ is heated by means of a small Bunsen burner N⁸, Fig. 3. The lever N is operated by the 40 end of a lever O, pivoted, as at O', to the frame F and furnished with projections O² O³, which work in conjunction with the cams B⁸ and B⁹. When the portions B¹⁰, B¹¹, and B¹² 45 of the cam B⁹, Fig. 2, pass beneath the projection O², the lever N is raised against the action of the spring N⁵, and, as will be seen by reference to Fig. 2, immediately following these portions are gaps, so that as the shaft 50 B rotates the lever L gives three sharp downward movements, causing the plate N² to tap the cigarette. The projection O³ then contacts with the portion B¹², and consequently the lever N is slightly raised again. After 55 the portion B¹² has passed from under the projection O³ the lever N descends and the plate N² rests upon the end of the cigarette under treatment, which has started rotating since the conclusion of the tapping operation and 60 smooths the tip. Continued rotation of the shaft B causes the frame G¹⁰ to reciprocate, and the rounded nose L⁵ of the extension L⁴

of the lever L lifts the lever N away from the cigarette while the latter is ejected from the holder D. 70

Beneath the plate N² and arranged so as to be just clear of the protruded cigarette end is a curved plate P. This plate is adjustably supported, as by screws P', from the bar G¹⁶ or an extension thereof. The function of this 75 curved plate P is to serve as a support for the end of the cigarette when it is being tapped by the plate N². There is preferably such a clearance between the plate P and the cigarette end that the latter is only likely to touch 80 the plate when it is struck by the tapper. The curved plate P or its support conveniently serves as a stop to limit the motion of the stop-lever F².

In order to bring the strips into more complete contact with the retainer G, a device R is provided. (Illustrated in perspective in Fig. 7.) This device comprises a block R', carried on the standard A⁹, having two projections R² and R³. The lower projection R² 90 is provided with a hole R⁴, which accommodates the pin G⁴ upon the segmental blocks G' of the retainer G, while the upper projection R³ is in the form of a spring. When the strip carried by its adhesion to the projections G³ of the retainer G, is brought by the reciprocation of that retainer against the block R', the hole R⁴ in the lower projection R² forces the pin G⁴ through the strip, while the spring projection R³ presses against the 95 upper end of the strip and brings that end into intimate contact with the adhesive matter upon the adjacent portion of the retainer. When cork or like material is used for the strips, there is some risk of adhesive matter 100 finding its way through the strip and onto the projections R² and R³, and this might result in the succeeding strip being pulled off by adhesion to these projections. To obviate this difficulty, means are provided for cleansing the projections R² and R³ automatically. A vessel R⁵, containing water, is attached to the standard A⁹, and a pad of felt or like material R⁶, attached to the block R', dips into 105 the water. A brush R⁷, carried by an arm R⁸, attached to a block R⁹, free to reciprocate upon a guide R¹⁰, supported by a standard A¹¹, moves over the pad R⁶ and the projections R² and R³, thus cleansing the projections from any adhesive which may be upon 110 them. The movement of the brush R⁷ is brought about by the end of the lever H¹⁶, which operates between the arm R⁸ and a pin R¹¹. 115

The action of the machine is as follows: 120 The cigarettes are placed in the chamber C and pass successively, as hereinbefore described, to the holder D. Suppose now that through the action of the cam B⁷ upon the friction-roller G¹² the frame G¹⁰ is reciprocated 125 toward the flexible gumming-band H. At the end of its stroke, as indicated in chain lines in Fig. 2, the retainer G comes into contact with that band and pressing against it 130

causes its upper portion to assume a curved form and to coat the adjacent surface of the retainer with adhesive, which has been previously applied to the band H by the brush H'. The frame G¹⁰ then returns and when above the container J remains stationary while a strip is presented to the lower portion of the retainer. This portion is not the one to which adhesive has just been applied, 5 but the one in front of it, which has, of course, been gummed during a previous operation of the machine. The retainer then continues 10 its motion and is rotated through an angle of approximately ninety degrees by the action 15 of the pawl G⁷. The strip which has just been applied to the retainer is now in an approximately vertical position, (see Fig. 2,) adhering to the projections G³ upon the right-hand side of the retainer G. The retainer 20 continues its motion and brings this strip into contact with the projections R² and R³ upon the block R', as shown in chain lines in Fig. 2. Continued rotation of the shaft B now results 25 in the retainer again commencing to travel toward the band H, and as it approaches the holder D the lifting device L L', &c., is raised and the front end of the strip on the top portion of the retainer G is lifted, and upon the lifting device L L', &c., being released 30 by the pawl M² comes into contact with the end of the cigarette. As the lifting device drops it passes down the gap between the segmental portions G' of the retainer G, and immediately afterward the lever N descends 35 and taps the newly-applied strip with the plate N². It should be mentioned that during the time the retainer travels from the container to the device R and back to the holder and during the tapping operation the 40 holder D is stationary, the plain part of the circumference of the disk D³ being adjacent to the teeth of the pinion D². After the plate N², carried by the lever N, has tapped the cigarette it rises and the holder D starts rotating, carrying with it the cigarette. The 45 plate N² then descends and remains in contact with the strip, which is consequently wrapped around the end of the cigarette smoothly. The retainer G then continues its 50 motion toward the band H without further rotation, and another face of the retainer is coated with adhesive. It will be seen that for every complete revolution of the shaft B the retainer G rotates for a quarter of a revolution; 55 but during this period a distinct operation is performed upon each of the segmental portions G' of the retainer G—namely, one is coated with adhesive, another (previously coated) has a strip presented to it, 60 the next has the strip more intimately applied to it, while the fourth gives up its strip to the cigarette. The finished cigarette is ejected by the plunger E during the time that the retainer G is moving from the container J to the device R and back to the holder D. The 65 stop F³ is moved downward and pushes the

cigarette slightly back in the holder D just after the plunger E has started on its backward stroke.

Although it is preferred to apply an adhesive 70 to the retainer and to use strips of material previously uncoated, yet, if desired, strips previously coated on one side with adhesive material may be employed, in which case they would be placed in the container 75 with the coated side uppermost and water or a similar moistening agent applied to the retainer.

I do not herein claim the delivery apparatus 80 shown, which forms the subject-matter of my pending application, Serial No. 4,986, filed February 12, 1900, nor do I herein claim the feed apparatus which forms the subject-matter of my pending application, Serial No. 4,985, 85 filed February 12, 1900.

What I claim as my invention, and desire to secure by Letters Patent, is—

1. In a cigarette-mouthpiece-applying machine the combination of a holder for the cigarette, a retainer for a strip, means for moistening the retainer, means for presenting a strip to and contacting it with the retainer, means for moving the retainer with the strip into proximity with the cigarette, and a lifting device to disengage the strip from the retainer and bring its under surface into contact with the cigarette. 90

2. In a cigarette-mouthpiece-applying machine the combination of a holder for the cigarette, a retainer for a strip, means for supplying adhesive to the retainer, means for presenting a strip to and contacting it with the retainer, means for moving the retainer with the strip into proximity with the cigarette, and a lifting device to disengage a portion of the strip 105 from the retainer and bring its under surface into contact with the cigarette.

3. In a cigarette-mouthpiece-applying machine the combination of a holder for the cigarette, a retainer for a strip, means for supplying adhesive to the retainer, means for automatically presenting a strip to and contacting it with the retainer, means for bringing the strip into more complete contact with the adhesive-coated surface of the retainer, means 110 for moving the retainer with the strip into proximity with the cigarette, and a lifting device to disengage a portion of the strip from the retainer and bring its under surface into contact with the cigarette. 115

4. In a cigarette-mouthpiece-applying machine the combination of a holder for the cigarette, a retainer for a strip, means for supplying adhesive to the retainer, means for automatically presenting the strip to and contacting it with the retainer, means for bringing the strip into more complete contact with the adhesive-coated surface of the retainer, means for moving the retainer with the strip into proximity with the cigarette, a lifting device to disengage a portion of the strip from the retainer and bring its under surface into 125

120

125

130

contact with the cigarette, a tapping and smoothing device and means for operating such device.

5. In a cigarette-mouthpiece-applying machine the combination of a holder for the cigarette, a retainer for a strip, means for supplying adhesive to the retainer, means for automatically presenting the strip to and contacting it with the retainer, means for bringing the strip into more complete contact with the adhesive-coated surface of the retainer, means for moving the retainer with the strip into proximity with the cigarette, a lifting device to disengage a portion of the strip from the retainer and bring its under surface into contact with the cigarette, a tapping and smoothing device, means for operating such device and a stationary support for the end of the cigarette under treatment.
10. 6. In a cigarette-mouthpiece-applying machine the combination of a holder for the cigarette, means for protruding the cigarette too far through the holder, means for partially returning the cigarette into the holder, a retainer for a strip, means for supplying adhesive to the retainer, means for automatically presenting the strip to and contacting it with the retainer, means for bringing the strip into more complete contact with the adhesive-coated surface of the retainer, means for moving the retainer with the strip into proximity with the cigarette, and a lifting device to disengage a portion of the strip from the retainer and bring its under surface into contact with the cigarette, substantially as set forth.

7. In a cigarette-mouthpiece-applying machine a holder for the cigarette, means for intermittently rotating the holder, a retainer having accommodation for a strip, means for intermittently reciprocating and rotating the retainer, a spring-controlled band, means for intermittently supplying the band with adhesive, a container for the strips, means for intermittently reciprocating the container, a relieving-piston within the container, means for intermittently reciprocating the piston, a lifting device to disengage a portion of the strip from the retainer and bring its under surface into contact with the cigarette and an inclined plane operating to raise the lifting device, substantially as set forth.

8. In a cigarette-mouthpiece-applying machine a holder for the cigarette, means for intermittently rotating the holder, a retainer having accommodation for a strip, and a pin which engages with the strip, means for intermittently reciprocating and rotating the retainer, a spring-controlled band, means for intermittently supplying the band with adhesive, a container for the strips, means for intermittently reciprocating the container, a relieving-piston within the container, means for intermittently reciprocating the piston, a block having two projections for bringing the strip into intimate contact with the adhesive-coated surface of the retainer one projection

having accommodation for the pin upon the retainer and the other being a spring, a lifting device to disengage a portion of the strip from the retainer and bring its under surface into contact with the cigarette and an inclined plane operating to raise the lifting device, substantially as set forth.

9. In a cigarette-mouthpiece-applying machine a holder for the cigarette, means for intermittently rotating the holder, a retainer having accommodation for a strip and a pin which engages with the strip, means for intermittently reciprocating and rotating the retainer, a spring-controlled band, means for intermittently supplying the band with adhesive, a container for the strips, means for intermittently reciprocating the container, a relieving-piston within the container, means for intermittently reciprocating the piston, a block having two projections for bringing the strip into intimate contact with the adhesive-coated surface of the retainer one projection having accommodation for the pin upon the retainer and the other being a spring, a lifting device to disengage a portion of the strip from the retainer and bring its under surface into contact with the cigarette, an inclined plane operating to raise the lifting device, a tapping and smoothing device and means for causing it to give a series of taps and then to rest upon the strip in process of application, substantially as set forth.

10. In a cigarette - mouthpiece - applying machine a holder for the cigarette, means for intermittently rotating the holder, a retainer having accommodation for a strip and a pin which engages with the strip, means for intermittently reciprocating and rotating the retainer, a spring-controlled band, means for intermittently supplying the band with adhesive, a container for the strips, means for intermittently reciprocating the container, a relieving-piston within the container, means for intermittently reciprocating the piston, a block having two projections for bringing the strip into intimate contact with the adhesive-coated surface of the retainer one projection having accommodation for the pin upon the retainer and the other being a spring, a lifting device to disengage a portion of the strip from the retainer and bring its under surface into contact with the cigarette, an inclined plane operating to raise the lifting device, a tapping and smoothing device, means for causing it to give a series of taps and then to rest upon the strip in process of application, and a stationary curved support for the end of the cigarette under treatment arranged so that it is normally just clear of the tipped end and operates during the period in which the cigarette is tapped substantially as set forth.

11. In a cigarette - mouthpiece - applying machine a holder, a plunger for protruding the cigarette too far through the holder, means for operating the plunger, a pivoted stop-lever for partially returning the cigarette into the holder, means for bringing the

stop-lever into a definite position relatively to the holder, a retainer having accommodation for a strip and a pin which engages with the strip, means for intermittently reciprocating and rotating the retainer, a spring-controlled band, means for intermittently supplying the band with adhesive, a container for the strips, means for intermittently reciprocating the container, a relieving-piston within the container, means for intermittently reciprocating the piston, a block having two projections for bringing the strip into intimate contact with the adhesive-coated surface of the retainer one projection having accommodation for the pin upon the retainer and the other being a spring, a lifting device to disengage a portion of the strip from the retainer and bring its under surface into contact with the cigarette and an inclined plane operating to raise the lifting device, substantially as set forth.

12. In a cigarette - mouthpiece - applying machine a holder for the cigarette, means for intermittently rotating the holder, a retainer having accommodation for a strip and a pin which engages with the strip, means for intermittently reciprocating and rotating the retainer, a spring-controlled band, means for intermittently supplying the band with adhesive, a container for the strips, means for intermittently reciprocating the container, a relieving-piston within the container, means for intermittently reciprocating the piston, a block having two projections for bringing the strip into intimate contact with the adhesive-coated surface of the retainer one projection having accommodation for the pin upon the retainer and the other being a spring, a lifting device to disengage a portion of the strip from the retainer and bring its under surface into contact with the cigarette, an inclined plane operating to raise the lifting device, a heated tapping and smoothing device, means for causing it to give a series of taps and then to rest upon the strip in process of application and a stationary curved support for the end of the cigarette under treatment arranged so that it is normally just clear of the tipped end and operates during the period in which the cigarette is tapped, substantially as set forth.

13. In a cigarette - mouthpiece - applying machine a holder for the cigarette, means for intermittently rotating the holder, a retainer

having accommodation for a plurality of strips and pins engaging with said strips, means for intermittently reciprocating and rotating the retainer, a spring - controlled band, means for intermittently supplying the band with adhesive, a container for the strips, means for intermittently reciprocating the container, a relieving-piston within the container, means for intermittently reciprocating the piston, a block having two projections for bringing the strip into intimate contact with the adhesive-coated surface of the retainer one projection having accommodation for the pin upon the retainer and the other being a spring, a lifting device to disengage a portion of the strip from the retainer and bring its under surface into contact with the cigarette, an inclined plane operating to raise the lifting device, a heated tapping and smoothing device, means for causing it to give a series of taps and then to rest upon the strip in process of application and a stationary curved support for the end of the cigarette under treatment arranged so that it is normally just clear of the tipped end and operates during the period in which the cigarette is tapped, substantially as set forth.

14. In a cigarette - mouthpiece - applying machine the combination of a flexible band a spring acting to keep said band normally straight, means for supplying the band with adhesive, a retainer having a circular surface to receive the adhesive, and means for intermittently reciprocating the retainer and bringing it into contact with the strip substantially as set forth.

15. In a cigarette - mouthpiece - applying machine, the combination of a counterbalanced tapping-lever, means for intermittently raising the lever, a spring to oppose the latter portion of the upward movement of the lever and to operate upon said lever for the first portion of its downward stroke, and a stop to intercept the spring after a portion of the stroke has been made, substantially as set forth.

In testimony whereof I have signed my name to this specification in the presence of two subscribing witnesses.

JOSEPH SAMUEL BEEMAN.
